UNITED STATES PATENT OFFICE

171,498

BOWL

Charles W. Hensley, Seneca, Mo.

Application December 6, 1952, Serial No. 22,587

Term of patent 14 years

(Cl. D44—15)

To all whom it may concern:

Be it known that I, Charles W. Hensley, a citizen of the United States, residing at Seneca, in the county of Newton and State of Missouri, have invented a new, original, and ornamental Design for a Bowl, of which the following is a specification, reference being had to the accompanying drawing, forming part thereof.

Figure 1 is a top plan view of a bowl showing my new design.

Figure 2 is a bottom plan view thereof.

Figure 3 is a transverse section on an enlarged scale of the bowl shown in Figure 1, the view

being taken substantially on line 3—3 of Figure 1.

Figure 4 is a side view on an enlarged scale of the said bowl.

I claim:

The ornamental design for a bowl, as shown.
CHARLES W. HENSLEY.
